FOLDABLE PINLESS STRETCHER

Robert J. Aston, Pittsburgh, Pa.

Application October 9, 1934, Serial No. 747,644

2 Claims. (Cl. 45—24)

The invention relates to a foldable pinless stretcher and more particularly to an adjustable stretching frame for curtains or other articles or materials to be stretched.

5 The primary object of the invention is the provision of a stretcher of this character, wherein the main frame is readily foldable when not in use, so that it can be stored within the least possible space, which also permits the same to be carried from point to point in a convenient manner, and upon this frame are carried clamps, these being adjustable and releasable so that the work to be stretched can be conveniently placed therein or removed at will and thus on the placing of such clamps upon the frame the material can be rendered smooth and stretched to the desired degree.

20 Another object of the invention is the provision of a stretcher of this character, wherein the material or article to be stretched can be firmly and securely held without in the least marring such material or article and without the use of pins, which frequently damage or mar the material or article when upon a stretching frame, the stretcher being susceptible of a wide range 25 of adjustment to accommodate material or articles of varying sizes.

25 A further object of the invention is the provision of a stretcher of this character which is extremely simple in its construction, thoroughly reliable and efficient in its purpose, novel in construction, light in weight, yet strong, durable, and inexpensive to manufacture.

With these and other objects in view, the invention consists in the features of construction, 35 combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a top plan view of a stretcher constructed in accordance with the invention, showing an article held thereby.

45 Figure 2 is a fragmentary perspective view of a table top, showing the clamp for the material or article to be stretched engaged therewith for subsequent attachment to the frame of the stretcher.

50 Figure 3 is a perspective view of the stretcher frame showing the clamp holding pieces in open position.

55 Figure 4 is a fragmentary vertical longitudinal sectional view taken on the line 4—4 of Figure 1.

Figure 5 is a vertical longitudinal sectional view through the stretcher when folded for non-use.

Similar reference characters indicate corresponding parts throughout the several views in the drawings.

5 Referring to the drawings in detail, A designates generally the main frame of the stretcher, it including the pair of open frame sections 10 and 11, respectively, these at adjacent meeting ends 12 being swingingly connected by hinges 13 10 so that said sections can be folded one upon the other for the storage of the stretcher, when not in use, in the least possible space.

The opposite side members 14 of the sections 10 and 11 carry clamping pieces 15, the side members 14 being cut away intermediate of the ends of the sections to accommodate said pieces 15 and such pieces at their outermost ends are swingingly connected to the companion sections of the frame A by winged nut-carrying bolts 16, while 20 the inner ends of these pieces are preferably provided with notches 17 opening through the inner faces thereof for the releasable reception of winged nut-carrying bolts 18 carried by the sections 10 and 11 of the frame A. At the top edges 25 of the pieces 15 matching the notches 17 are bearing plates 19 for the nuts 20 of the bolts 18 so as to prevent the wearing of these pieces on detachably securing said pieces aligned with the side members 14 of the frame A, the purpose of the 30 pieces 15 being hereinafter fully described.

Separably carried by the sections 10 and 11 of the frame are clamp carrying cross pieces 21, each in the form of spaced bars, having secured at their top sides on opposite ends thereof bearing plates 22, these being adapted to overlap the side members 14 of the frame A and bridged by the pieces 15 so as to secure the said bars 21 upon the frame and in the selected adjusted relation to each other.

40 Each cross piece has approximately central thereof a longitudinally disposed space 23 into which may be tucked or threaded fringe or other edging to an article or piece of material to be stretched, while arranged at intervals on the 45 bar 21 at one side of the space 23 therein are fixed or stationary bolts 24 received in a series of slotted clamping blocks 25, these being provided with elongated slots 26 accommodating the bolts 24 and allowing for a determined range of 50 adjustment of said blocks, the bolts being fitted with winged nuts 27, and by tightening the blocks upon the bar 21, a piece of material can be attached thereto, these bars 21 being attached at opposite ends of the piece of material or article 55

- to be stretched and, as is apparent from Figure 2 of the drawings, the said bars 21 can be attached when laid upon a table top 28 for convenience in so doing. Thereafter, the bars 21 attached to the 5 piece of material or article 29 are placed upon the frame 13 and pulled apart the desired degree for the stretching of the piece of material or article 29 and thereafter made fast by the pieces 15 hereinbefore described.
- 10 One of the end pieces 12 is provided with a longitudinally disposed slot 30 for accommodating bolts 31 carrying winged nuts 32, these adjustably fastening clamping blocks 33 in place so that they can be engaged with the longitudinal edges 15 of the piece of material or article 29 intermediate of its attached ends to hold the same flat and smooth, as is clearly apparent in Figure 1 of the drawings.
- 20 The ends 12 at their uppermost faces and likewise the bars 21 are provided with lineal scales 34 for measuring purposes of the piece of material or article 29 as placed upon the stretcher, so that the original measurements of such piece of material or article 29 can be retained in the 25 stretching action by the stretcher in its use.

The section 10 and section 11 of the frame A

are latched by hooks 35 to hold the same unfolded and in a folded condition in the same plane with each other when the stretcher is in use.

From the foregoing it is thought that the construction and manner of operation of the stretcher will be clearly understood and, therefore, a more extended explanation has been omitted.

What is claimed is:

1. A stretcher of the character described comprising an open frame, cross bars fitted with the 10 frame for longitudinal adjustment thereon and separable therefrom, retaining pieces carried by the frame and securing the cross bars thereon, clamping blocks adjustably carried by the cross bars, bars intermediate of same frame and disposed crosswise thereof, and adjustable clamping blocks on one of said intermediate bars.

2. In a stretcher of the character described, a sectional foldable frame, cross bars separably and adjustably carried by said frame on the respective sections thereof, retaining pieces swingingly carried by the frame and securing the cross bars thereto, means for latching the retaining pieces in securing position for the cross bars, and clamping blocks adjustably carried by the cross bars.

ROBERT J. ASTON.
